UNITED STATES PATENT OFFICE.

ALIPIO C. BARTHOLO AND MANUEL PERRY, OF NEW BEDFORD, MASSACHUSETTS.

MUSIC-LEAF TURNER.

Application filed February 15, 1921. Serial No. 445,124.

To all whom it may concern:

Be it known that we, ALIPIO C. BARTHOLO and MANUEL PERRY, citizens of the United States, residing at New Bedford, in the county of Bristol and State of Massachusetts, have invented certain new and useful Improvements in Music-Leaf Turners, of which the following is a specification.

The invention has for an object to effect improvements in such devices aiming particularly toward their simplification so that they may be put upon the market at a low price and made popularly available. It is also an aim to provide a construction in such devices which will be efficient for the purposes in view. A particular object is to give a novel means for the mounting of music in such devices, whereby expensive, heavy or awkward clamping or securing devices are rendered unnecessary. A further purpose is to give an improved construction in turning arms in such an appliance. A still further aim is to give a novel and desirable structure in the base element and mounting for the leaf turning elements.

Additional objects, advantages and features of invention will appear from the construction, arrangement and combination of parts hereinafter set forth and shown in the drawings, wherein:

Fig. 1 is a front elevation of a turner embodying our invention shown in open position, with sheet music engaged therein.

Fig. 2 is a horizontal sectional view showing the turning arms in plan, with the clips removed, the device being closed.

Fig. 3 is a fragmentary top view showing music engaged with the device,

Fig. 4 is a fragmentary front elevation of the music securing pivot element,

Fig. 5 is a fragmentary horizontal sectional view looking upwardly, showing the last mentioned element,

Figs. 6 to 13, inclusive, are views of the turning arm blanks represented in the order of assembly from bottom to top.

Fig. 14 is a fragmentary vertical cross section showing the mounting of the turning arms,

Fig. 15 is a perspective view of one of the arms and clips.

There is illustrated a music leaf turner comprising a backing portion which is adapted to be closed in the form of a book.

It includes a vertical central back piece 20,

formed of sheet metal, rectangular in cross section and oblong transversely, to the back surface of which there is secured by suitable adhesives a flexible fabric 21 which projects 60 beyond the vertical edges of the back piece and has secured to its edge portion respective cover pieces 22, which may be of pulp-board or other suitable material. The outer surfaces of the whole are covered with a suitable 65 ornamental material 23, such as leather, or paper.

The back piece is in the form of a rectangular tube, and upon this a short distance from its upper end there is mounted a 70 combined music retaining clip and pivot formed of wire, including a base eye portion 25 through which a screw 26 may be engaged to secure the clip upon the back 20. From the eye the wire is recurved to receive 75 a second mounting screw, and then extended downwardly and recurved upwardly to form a spring loop 27. From this loop the wire is continued to provide a pointed semi-circular music-piercing piece 28 disposed in 80 a horizontal plane at right angles to the plane of the eye and the spring loop before mentioned. The extremity of the piercing member extends inwardly at a distance from the eye 25 and a short distance into an aperture 29 in the back. The construction of this device is such that by grasping the member 28 and drawing outwardly thereon, the point may be withdrawn from the apertures 29 sufficiently for the insertion of the upper 85 left hand corners of music leaves thereunder, and release of the piercing member will permit it to pierce the sheets presented thereunder, which may then be moved pivotally, sliding upon the piercing member. If desired, the music may be perforated suitably to fit loosely upon the member 28.

A short distance above the lower extremity of the back member 20, a horizontal ear 30 is pressed from its forward side, and a short distance therebelow a parallel similar ear 31 is thrust forwardly into vertical alinement therewith from the back portion of the back member 20. A pintle 34 is engaged through the ears 30 and 31 and 100 screwed into a cylindrical element 35 below the ear 31, to form a support for the leaf turning arms.

Eight leaf-turning arms, numbered 36 to 43 inclusive are illustrated, having 110 apertured horizontal ears 44 around the pintle, snugly held between the ears

30 and 31 of the back 20. The arms are of thin sheet metal disposed in vertical planes and the ears 44 are spaced on the heels 32 of the arms, a proper distance 5 to allow nesting of the arms in a vertical horizontal plane. The arms 36 to 43 are progressively lengthened, and provided at their extremities with out-standing ears 46 between which clip elements 47 are secured, 10 whereby a sheet of music may be held in fixed relation to the respective arms. At the outer end of said arms upwardly extending clip lugs 47' are formed integrally therewith cooperating with the clip elements 47 so that 15 a sheet of music may be held therebetween. The clip elements 47 may be spring-pressed in any familiar way. It should be noted that the clip elements have a finger portion extending downwardly therefrom which 20 serve both as a clip operating device, and as a means by which the arms 43 may be operated for shifting music, as may be readily appreciated from Fig. 1 and Fig. 2. At their inner ends, the arms are formed 25 with heel portions 32 extending downwardly from the respective arms having vertical edges adjacent the horizontal ears 44 and adapted to bear either upon the next adjacent lower ears 44, or upon the supporting 30 element 35. The leaf-turning arms are thus held securely elevated at their outer parts. The arms are in the form of plates all stamped from sheet material, and are arranged with their ear portions 44 successively 35 lower, in numerical order, as shown in Figures 6 to 18, so that they may lie closely in nested relation when closed, permitting closure of the device readily.

In use, sheet music is adjusted in the device as shown in Fig. 1, and leaves thereof clamped to respective arms by means of the clips 47, as shown and indicated. All of the leaves and arms are first positioned to the right, as will be understood, and with

the parts in this position, each of the clips 45 47 is in spaced relation with, and a little in advance of the one adjacent so that it may be readily engaged manually without liability of operating more than one at a time, permitting manual turning of the leaves 50 with either hand with great certainty and rapidity.

What is claimed:

1. In a music-leaf turner, a back element comprising a tube rectangular in cross section, music retaining means on the front thereof, the front part of the tube at the lower end being turned outwardly to form an upper pivot ear, the rear part of said tube being turned in a similar direction at a lower level to form a lower pivot ear, the sides of said tube being extended a distance below the last named ear, means engaged with the tube to support it above a music rest, a pintle engaged in said ears, and music turning arms pivoted thereon.

2. In a device of the character described, an improved music turning arm comprising a plate of sheet metal having a pivot ear formed at one end thereof and turned in a plane at right angles to the vertical medial plane of the plate, and a heel element extending downwardly therefrom integral, and in a vertical plane with, the body, said plate having an upwardly extending clip lug at the outer end, and parallel vertical ears adjacent the base of the lug, and a clip device pivoted between said ears having an operating portion extending downwardly by which the clip may be operated, and by which the arms may also be turned.

In testimony whereof we have affixed our signatures in presence of two witnesses.

ALIPIO C. BARTHOLO.
MANUEL PERRY.
